UNITED STATES PATENT OFFICE

2,442,559

METHOD OF MAKING FORCE
LASTED SHOESSaul L. Erlich, Malden, Mass., assignor of one-
half to Abraham M. Rogoff, Boston, Mass.

Application February 12, 1945, Serial No. 577,575

1 Claim. (Cl. 12—142)

1

This invention relates to a method of making force lasted in shoes, particularly women's shoes having open toes made by the cement process and which may either be made with or without platforms. The invention is directed to improvements particularly in methods of manufacture.

Women's shoes are now commonly made with open toes and open backs. One of the principal items of expense is the skilled labor required for the lasting operation. Since, even though the provision of open toes and the elimination of the quarter portion makes the lasting easier, it has still not been commercially practical to eliminate the lasting step and still obtain shoes which will properly fit the foot and present an attractive appearance.

It is the object of my invention to provide an improved method of making shoes of the character described which will eliminate the necessity of skilled labor in lasting the shoes.

According to my invention, the lining layer is first cemented to the outer layer of the upper in the flat, leaving, however, free marginal portions. A sock lining is then stitched to the free marginal edges of the lining layer in such a manner as to fix the size of the vamp before it is slipped upon the last. This step of assembling the vamp upon the last is then a relatively simple operation which might be performed by unskilled labor as no pulling-over is required. The free marginal edges of the outer layer of the upper may be easily turned down and cemented to the inner side which is laid over the sock lining. The shoe may then be finished in any suitable manner.

Further objects and advantages of my improvements will be more readily apparent from the following descriptions of preferred embodiments thereof as illustrated in the accompanying drawings, in which:

Figure 1 is a bottom view of one half of the upper showing the lining layer cemented in position on the outer layer;

Figure 2 is a similar bottom view of the other part of the upper;

Figure 3 is a bottom view showing the two parts of the upper after they have been attached at the toe;

Figure 4 is an enlarged fragmentary view showing the underneath side of the toe-portion of the vamp after binding strips have been attached and also illustrating the manner in which a free marginal edge of the lining layer may be turned up for the subsequent stitching operation;

Figure 5 is a bottom view showing the vamp

2

after the sock lining has been stitched to the lining layer and the vamp has been assembled on a last;

Figure 6 is a bottom view showing the shoe upon the last after the marginal edges of the outer layer of upper have been turned in and cemented in position;

Figure 7 is a cross-sectional view taken through the toe of the shoe illustrating the manner in which the marginal edges of the outer layer of the vamp may be turned over a thin insole;

Figure 8 is a view similar to Figure 7 but showing a modification in which an invisible platform has been inserted.

Figure 9 is a side view of a shoe with a concealed platform showing the heel portion of the sock lining ready to be cemented;

Figure 10 is a view similar to Figure 4 but showing a modified method of freeing the lining flaps;

Figure 11 is a view similar to Figure 10 but showing a still further modification; and

Figure 12 is a side view of a completed shoe having a platform; and

Figure 13 is a fragmentary side view of a shoe having a half platform.

The parts of the outer and lining layers of the vamp are first cut according to pattern such as to the shapes illustrated in Figures 1 and 2 in which 10 and 12 are the two halves of the outer layer of the upper, while 14 and 16 comprise the two halves of the lining layer of the upper. Where the shoes have open backs, it is customary to provide a heel-strap portion as indicated 18. The lining layer 14 is cemented to the outer layer 10 while the lining layer 16 is similarly cemented to the outer layer 12. The marginal edge 20 of the part 14 and the marginal edge 22 of part 16 are left free and uncemented and it will be noted that the edges 20 and 22 of the lining parts are inwardly spaced relatively to the marginal edges 24 and 26 of the outer part.

In Figures 1 and 2 there are shown cuts or slits 28 and 30 at the toe and 32 and 34 at the back in the lining parts 14 and 16. In this form, the cuts are made perpendicular to the marginal free edges of the lining parts and parallel to the end portions of the parts. These cuts which are formed by dieing out the lining parts permit turning up the marginal portions 20 and 22 after the binding strips have been attached as later described.

The next step is to close the front of the upper by attaching the parts as indicated by the seam 36 in Figure 3. Next the top of the upper and

the open back and toe edges are suitably finished such as by pressing or French cording. In this step a binding strip 38 is attached to the underside of the vamp to cover the seam 36 and extending along the underside exposed edges of the open toe as shown at 40. It will now be apparent that the slits 28 and 30 previously described, permit the binding strip portions 40 to be applied while still leaving the flaps 20 and 22 of the lining free to be turned up. It will be understood that the rear edges of the upper are similarly finished.

Next a sock lining 42 is stitched to the free flaps 20 and 22 of the lining, as shown by the lines of stitching 44 in Figure 5. It will be understood that the sock lining is made of fabric and may consist of two layers; one a finished fabric for the visible surface of the sock lining and the other a reinforcing lining which is cemented thereto.

The cutting of the patterns for the upper lining and the sock lining fixes the size and shape of the vamp so that it closely fits the last when assembled thereon. Therefore, it is a relatively simple operation to slip the vamp on to the last. Since the outer layer of the upper is cemented to the lining layer, it does not need to be pulled or stretched. After the upper has been placed on the last, a thin flexible innersole 46 having an attached shank stiffener 48 is cemented in position over the sock lining. The innersole 46 may be a relatively cheap material such as pasteboard. The toe portion of the sock lining 50 may be turned over and cemented to the innersole 46 and the marginal edges 24 and 26 of the outer layer of the upper may also be turned over and cemented to the innersole. This is a relatively simple step since it is not necessary to pull and stretch the upper as in customary lasting operations.

The shoe may then be finished by applying an outsole 42 and heel 53. If desired, before applying the outsole, a platform 54 may be cemented in position. The platform will have its exposed edges fabric-covered in the usual manner. Instead of making the shoe with an exposed platform, a concealed or invisible platform 56 may be used as shown in Figure 8 in which case the marginal portions 24 and 26 of the outer layer of the upper will have been cut to provide a larger amount of lasting allowance. In another form the shoe may be made with a half platform 57 as shown in Figure 13.

Referring to Figure 7, it will be noted that the provision of the innersole 46 allows the stitched edges of the upper lining and sock lining to be covered as the marginal portions 24 and 26 are turned in without causing a bulge. Thus the inner surface of the shoe remains smooth since the stitched edges are turned down around the edges of the innersole as shown in Figure 7.

The cuts or slits 28 and 30 previously described constitute only one form of freeing the edges of the lining. Figure 10 shows another method in which, before applying the binding 40, the corner portions 58 and 60 of the lining 14 and 16 are turned back as shown in Figure 10, thereby leaving the free flaps 20 and 22. One further method

is illustrated in Figure 11 in which slits 62 and 64 have been cut in the lining parts 14 and 16 parallel to the free edges thereof so that the end portion 66 of the flap 22 may be turned up before the binding 40 is applied and laid freely over the binding as shown at the top portion of Figure 11. Instead of slitting or folding, the corners could be cut out but the methods described hold the end portions of the lining more strongly against 10 pulling loose from the binding strips.

Before the heel is attached, the heel part of the last may be pulled out in order to permit folding the free part of the sock lining forward toward the toes. The heel part of the last is then inserted 15 and the heel attached. After the last is removed, the free heel part 68 of the sock lining 42 is laid down and cemented to the innersole.

The present invention is an improvement over the usual California process followed in making 20 platform shoes. In one form of the California process, a wrapper is attached to the upper and a wrapping machine must be used for pulling the wrapper over the platform.

In my method, the platform, either a full platform, as in Figure 12, or a half platform, as in 25 Figure 13, may be finished by binding the edges before it is applied to the shoe. The wrapping machine is eliminated. The appearance of the shoes made by my method is better than shoes 30 made by the California process since the platform is regular in appearance; that is, the binding is smooth and evenly applied to the platform; whereas in the California process, the wrapping of the platform often results in uneven binding. 35 It should be further understood, that my method permits the use of only a half platform and shoes of this character are much desired. The half platform can not be used by the usual California process construction. The half platform may be visible or concealed in my method.

I claim:

The method of making an open toe shoe which consists in cementing a lining layer to an outer layer to form an upper, the marginal edge of the lining layer being free and uncemented, binding the vamp at the open toe, the binding being supplied in such a manner as to permit turning up the free and uncemented edge of the marginal lining, then stitching a sock lining to the upper lining, inserting a last and finishing the shoe.

SAUL L. ERLICH.
